DESIGN FOR AN ASH TRAY

William Helwig, Milwaukee, Wis.

Application August 8, 1944, Serial No. 114,782

Term of patent 14 years

(Cl. D85—2)

To all whom it may concern:

Be it known that I, William Helwig, a citizen of the United States and resident of Milwaukee, county of Milwaukee, and State of Wisconsin, have invented a new, original, and ornamental Design for Ash Trays, of which the following is a specification, reference being had to the accompanying drawing, forming a part thereof.

The figure is a perspective view of an ash tray showing my new design.

I claim:

The ornamental design for an ash tray, as shown.

WILLIAM HELWIG.
